UNITED STATES PATENT OFFICE

JOSEPH AUGUSTIN BOMBARD AND ROLAND JAMES ROGERS, OF SARANAC LAKE,
NEW YORK

CAR VENTILATOR

Application filed September 8, 1930. Serial No. 480,565.

This invention relates to ventilators and more particularly to a ventilator for use in connection with a railway car, although it is to be understood that it may be applied to any structure for which it may be found suitable. The present invention constitutes an improvement upon the construction shown in Patent, No. 1,746,009, obtained by me and Joseph A. Bombard February 4, 1930.

One object of the invention is to provide a car ventilator adapted to be applied to a window frame or other portion of a car in operative relation to an opening formed therein whereby fresh air may pass into the car and air within the car sucked outwardly when the car is in motion.

Another object of the invention is to provide an improved closure for a neck extending through an opening in the window frame or car wall and so mount this closure that it may be easily moved to a closed or to a partially or fully opened position and thereby control passage of air into and out of the car.

Another object of the invention is to so mount the closure that its movements through the neck may be guided and the extent of movement limited, thereby permitting the closure to be very easily moved to a closed or an opened position and at the same time prevent the closure from being drawn out of the neck too far when opened.

Another object of the invention is to provide improved means for guiding passage of air through the ventilator when the closure is open and very effectively prevent inwardly and outwardly moving air from interfering with each other and becoming intermingled.

Another object of the invention is to provide the closure with walls through which air may pass having screening so applied thereto that there will be no danger of the screening catching against walls of the neck into which the closure fits and becoming detached or loosened when the closure is moved to adjusted positions.

Another object of the invention is to provide a device of this character which will be very neat in appearance and of such construction that it will operate properly with a car moving either forwardly or rearwardly.

The invention is illustrated in the accompanying drawings, wherein

Figure 1 is a perspective view looking at the interior of a car having the improved ventilators applied to its window frames,

Fig. 2 is a view in elevation looking at the ventilator from outside the car, portions of the ventilator being broken away,

Fig. 3 is a longitudinal sectional view taken on the line 3—3 of Fig. 2, and

Fig. 4 is a transverse sectional view taken on the line 4—4 of Fig. 3.

The ventilator is adapted for use in connection with a railway car, such as shown in Figure 1 and indicated in general by the numeral 1, and in this figure the ventilators 2 have been shown applied to the window frames 3, but it is to be understood that they could be mounted in other positions if so desired. These ventilators are of a duplicate construction and each is formed as shown in Figures 2, 3 and 4.

Each ventilator has an elongated hollow body 4 formed of metal and this body increases in depth towards its ends which are open. Screens 5 are mounted in the body in spaced relation to its ends and at its ends are disposed other screens 6 which together with the screens 5 serve to prevent cinders from blowing into the open end of the body facing the direction in which the car is moving. It should be noted that the open ends of the body are disposed in planes converging downwardly so that rain can not easily drive into the ventilators and that since the bottom of the body slopes downwardly toward its open ends any rain which may enter the body will drain out of the same. The inner side wall 7 of the body is formed intermediate its length with an opening and about this opening is disposed a neck 8 which is engaged through an opening 9 formed in the window frame or wall of the car. This neck fits snugly in the opening and when screws 10 are passed through the ears 11 extending from the ends of the inner wall and engaged in the window frame the ventilator will be very securely held in place. The collar 8 and the opening enclosed thereby are elongated longitudinally of the ventilator and the length is such that

the collar may be divided into end sections of such dimensions that air can very easily pass through the neck into and out of the car.

In order to close the open end of the neck and control passage of air through this neck, there has been provided a closure 12. This closure has a head 13 formed of sheet metal and walls 14. The head is of greater dimensions than the neck and of the same outline and the walls are of the same outline as the neck and of such dimensions that the closure has snug telescoping fit within the neck, as clearly shown in Figures 3 and 4. Therefore, the closure may be slid through the neck into and out of a closed position and when closed marginal portions of the head will bear against a facing band 15 secured against the inner face of the window frame in overlapping relation to the opening 9 and walls of the neck. The closure wall is of an open construction in order to permit free passage of air when the closure is open and has circumferentially extending strips or bands 16 connected by spaced bars or strips 17. Screening 18 is secured against the inner surfaces of the walls and serves very effectively to screen air passing through the closure as well as constituting a reinforcement for the walls. Therefore, the closure may be grasped by its handle 19 and thrust into the neck or drawn outwardly therefrom without danger of bending the strips 14. A partition or plate 20 is secured in the closure intermediate its length, and from an inspection of Figures 3 and 4 it will be seen that this plate extends transversely in the closure with one end fixed to the head 13 and its side edges secured to the walls of the closure. A companion partition 21 is mounted in the body and this partition consists of plates or sheets 22 which are secured to the outer side wall of the body and are curved, as shown in Figure 3, so that they extend from the outer side wall in converging relation to each other. Reduced portions 23 of the partition plates 22 extend into the neck in parallel relation to each other and these reduced end portions which are of less length than the depth of the neck have their free ends bent to form lips 24 extending diverging relation to each other. By this arrangement the lips will serve to guide the partition plate 20 between the reduced extensions 23 of the partition plates 22 when the closure is fitted into the neck and since the plates from which the partition 21 is formed are resilient they will have close contacting engagement with opposite side faces of the partition plate 20 and thereby cause the tubular body of the ventilator and its neck to be divided into air passages leading from opposite ends of the body and at their inner ends extending through the neck. Since the body portion and neck of the ventilator have been divided into separate air passages, air may pass inwardly through one air pas-

sage into a car when the closure is opened and air sucked out of the car through the other air passage when a car is in motion. From an inspection of Figure 3, it will be readily seen that air may pass into and out of a car through the ventilator no matter in which direction the car is moving. It is desired to guide and limit movement of the closure and in order to do so there has been provided posts 25 carried by the ventilator body and projecting into the neck near opposite ends thereof and stems 26 secured against the inner face of the closure head near opposite ends thereof. The posts are hollow and slidably receive the stems and each stem carries a pin 27 which projects transversely therefrom and is engaged through a slot 28 formed longitudinally in its cooperating post. Therefore, sliding movement of the closure will be guided by the stems which are slidably received in the hollow posts and the fact that the stems carry pins engaged through slots in the posts will limit sliding movement of the stems and thereby prevent the closure from being drawn outwardly beyond a position in which it is engaged in the neck. It will thus be seen that there will be no danger of the closure being drawn out too far by an inexperienced person opening the ventilator.

Having thus described the invention, we claim:

A car ventilator comprising a hollow body open at its ends and having a side wall formed with an opening intermediate its length, a neck about the side opening projecting transversely from said body, a partition in said body disposed transversely thereof and extending through the side opening into said neck and dividing the body into air passages having ends extending into said neck, a closure for said neck slidable into and out of a closed position, posts in said body at opposite sides of said partition, said posts being hollow and each formed with a longitudinally extending slot, and stems carried by said closure and slidably received in said posts to guide movement of the closure, said stems having pins engaged in the slots of the posts to limit movement of the closures.

In testimony whereof we affix our signatures.

JOSEPH AUGUSTIN BOMBARD. [L. S.]
ROLAND JAMES ROGERS. [L. S.]
